LIPSTICK CASE

Albert Gelardin, New York, N. Y.

Application May 3, 1947, Serial No. 745,700

17 Claims. (Cl. 206—56)

1

This invention relates to spring-actuated lipstick cases and, more particularly, to novel propel-repel lipstick cases which are spring-actuated, and which are free from binding.

In my application Serial No. 625,801, filed October 31, 1945, I have disclosed and claimed novel lipstick holders wherein the cup receiving the lipstick is advanced and retracted by means of a rotated, compression spring. In my said application, the desirable advantages were attained by the provision of special, apertured spring housings, secured in and to the bases of lipstick holders, the spring being rotatable therein; under compression, as well as rotatable in a contrary direction to be released from such compression and to expand to full, unrestrained pitch, thereby advancing the lipstick carrier in the casing.

I have now found that propel-repel, or retractile lipstick carriers or cases can be spring-actuated by the provision of simple spring-guiding and retaining means, having diametrically oriented bearing points or bearing surfaces, which are mutually and vertically displaced by an amount equivalent to one-half the free pitch of the spring. With such an arrangement, as will appear more fully hereinafter, there is no lateral binding or gripping of the spring when it is rotated in place in the lipstick casing. This insures a desired rectilinear travel of the lipstick cup or carrier which is normally mounted for unrestricted to-and-fro travel along the length of the lipstick casing or tubular container.

It is, therefore, among the features of novelty and advantage of the present invention, to provide novel lipstick cases of the propel-repel type in which compression springs are utilized to advance and retract the lipstick cup or carrier, the said springs being secured at their ends to the cups or carriers and to rotatable caps which rotate the springs in and out of contact with guiding or bearing surfaces which are formed in and cooperate with the casing in special orientation to impose a force on the medial or intermediate section of the spring effective to keep the axis of the spring substantially coincident with the axis of the tube, while a top section of the spring between such points and the carrier is fully expanded, and the bottom section which is connected to the rotatable cap or actuator is compressed between said bearing points or surfaces and the base of the said cap.

Additional features of novelty and advantage of the invention herein will comprise novel casing structures and rotatable bases, together with locking sleeves or casing segments, all of which are mutually secured in rotatable, interlocking engagement.

The above and other desirable features of novelty and advantage of the present invention

2

will be described in the accompanying specification, and illustrated in the drawings, certain preferred embodiments being shown, by way of example only, for, since the underlying features may be incorporated in other specific devices, it is not intended to be limited to the ones here shown, except as such limitations are clearly imposed by the appended claims.

In the drawings, like numerals refer to similar parts throughout the several views, of which

Fig. 1 is an elevation of a lipstick case embodying the principles of the present invention;

Fig. 2 is a vertical section, taken on line 2—2 of Fig. 1;

Figs. 3, 4 and 5 are horizontal sections taken on lines 3—3, 4—4 and 5—5 of Fig. 2;

Fig. 6 is a perspective view of a special barrier frame and guide member;

Fig. 7 is an exploded view of the lipstick case parts illustrated in Figs. 1 and 2;

Fig. 8 is a perspective view, partly in phantom view, of a modified form of lipstick casing;

Fig. 9 is a vertical section taken on line 9—9 of Fig. 8;

Fig. 10 is a fragmentary vertical section similar to Figs. 9, showing a modified form of spring barrier construction;

Figs. 11 and 12 are horizontal cross-sections taken on lines 11—11 and 12—12 of Fig. 9; and

Fig. 13 is an exploded view of the lipstick case shown in Figs. 8 and 9.

Referring now to the form of lipstick cases illustrated in Figs. 1 to 7 of the drawings, the novel lipstick holder will be seen to comprise a tubular casing or wall member 10, an actuating member or base 20, a lipstick carrier 30, a helical spring, cup actuating member 40, and a barrier frame and guide member 50.

The tubular wall member 10 comprises a generally cylindrical body portion 11, having a peened or domed upper end 12, defining an aperture 13. The open bottom 14 of the tube is provided with a plurality of radial slots 15, at least two of which are diametrically opposed, as shown, and severally defining spring fingers 16 therebetween. A horizontal groove, or indentation, 17, is formed in the wall 11 near the bottom of the fingers 16. This groove is shown as continuous and defining an internal ridge, raised annulus, or bead 17'. However, this bead may be formed as a row of spaced, embossed or raised dots. An outer sleeve or ferrule 18 is fitted over the bottom of wall 11 in a tight, friction fit, so as to mask the slots 15, as will be described more in detail hereinafter.

The base 20 comprises a generally cup-shaped member, having a cylindrical wall 21, with a peripheral groove 22 therein. The wall 21 is joined to, or made integral with, a flanged bottom 23 having a peripheral flange section 24. A slotted

pin or post 25 is formed or secured in the center of the well 26, defined by the cylindrical wall 21 and the flanged bottom 23, and receives the spring 40.

The lipstick carrier or cup comprises a cup-shaped member 30, with a vertical wall 31, apertured base 32 with a central aperture 33, and a hollow rivet 34 securing the upper end 41 of the spring 40. The wall 31 of the cup is provided with a plurality of peripheral ridges or radial guide members 35, in loose bearing engagement with the inside of wall 11. A lipstick mass 36 of suitable texture, color and shape, is contained in the cup and extends thereabove, being adapted to be exposed for use when the cap 20 is rotated to release the actuating spring 40. When the lipstick mass has worn down, or worn away, to a point where it is no longer usable, it is replaced.

The radial members 35, as illustrated, are so disposed with respect to the top edge of wall 31 of the cup, as to permit the said top edge to project through opening 13 of the tubular wall 11 when the cup is propelled to its topmost position, with the guide elements 35 abutting thereagainst, and being retained by the peened over shoulder 12 of the casing. This permits the cup to be advanced to its fullest extent in the tube or casing 11 and clear the mouth thereof to permit the insertion of replacement lipstick masses, as well as removal of stubs of the same.

The helical compression spring 40 includes a top terminal loop 41, secured in locking engagement with eyelet 34 of the cup carrier, and a bottom loop or locking section 42 engaged in and by the slotted pin 25 of the base member 20. The upper, fully expanded section of the spring, is designated by the numeral 43, while the lower, compressed section, contained within the cylindrical casing formed by section 21 of the bottom, is designated generally by the numeral 44. An intermediate section 45 is threaded in and between the spaces or barrier sections 51, 52 of the guide member 50.

The spring guide and retaining member or barrier frame 50 comprises a flat frame or stamping of metal or plastic, of generally rectangular shape, and forming parallel cross bars 51, 52 joined at their ends by integral spacers 53, 54. The cross bars and spacers of member 50 will be seen to define a frame comprising a rectangular inner apertured space 55, through which the intermediate section 45 of the spring is threaded. It will be noted that the lower ends of cross bar 51 provides a bearing surface for the upper portion or turn 45 of the spring, as indicated at 46, while the lower edge of cross bar 52 provides a bearing for the upper section 47 of the compressed portion 44 of the spring. The vertical distance between bearing points 46 and 47 is equal to one-half the free pitch of the spring.

The operation of this form of the novel lipstick case will be apparent from the above description. The cup member 30 is secured by and to the upper end 41 of spring 40, the lower end being threaded through the aperture 51 of guide member 50. The lower end 42 of the spring is then secured in position by the slotted post 25 of the base, and the barrier frame or guide 50 is inserted into and retained by opposed radial slots 16 of casing 10. The base 20 is then forced upwardly into the casing, compressing the spring 40 against the bottom edge 52 of member 50, the upper edge of cylinder 21 serving as an abutment for the said bottom edge. The base or cap 20 is rotatably locked in place by the inter-engage-

ment of its peripheral groove 22 with the bead 17 of the wall member 11 of sleeve 10. Thereafter, ferrule 18 is forced down over the assembly, as illustrated, and the spring fingers 16 are thereby held under compression, maintaining the bead 17 positively engaged in and interlocked with the groove 22 of cap 20, and the barrier member 50 is prevented from lateral movement in or out of the slots 16.

This particular form of lipstick holder will be seen to comprise relatively simple, positive-acting structural members of metal or other suitable material, such as plastics. It can be assembled readily to form a propel-repel lipstick holder in which the operative parts are fully protected, and in which the lipstick is available down to the base or butt, due to the carrier being extensible through and beyond the opening 13 to permit ready access thereto.

In Figs. 8 to 13 there are shown modified lipstick cases or holders in which the spring-guiding or barrier members are formed in and as part of the casing, and a special ferrule is associated with the rotatable cap member to lock the parts together, as well as to serve as a driving or rotating member for the cap.

The forms shown are generally similar to those illustrated in Figs. 1 to 7, with minor variations, and prime numerals will be used to designate the parts which conform to those illustrated and described in Figs. 1 to 7. As shown, the casing 10' comprises the usual tubular body 11', with peened in top 12' defining the discharge aperture 13'. Everted flanges 14' are formed at the bottom of finger sections 16', defined and separated by radial slots 15'. In the form illustrated in Figs. 8, 9 and 13, a pair of opposed fingers 16' are formed with ridges or barriers 17', 18', providing bearing surfaces which are vertically displaced by an amount equivalent to one-half the free pitch of the spring. In the modified form illustrated in Fig. 10, the barriers or indentations 17', 18' are respectively substituted by rivets or pins 17'', 18'', similarly positioned and similarly functioning. The lipstick carrier cups 30' are generally identical with the cups 30, being secured in the same manner to the spring 40. However, the cups are spaced and guided in the casing 10' by horizontal guide members 35' which are formed at the bottom and adjacent the top of the outer walls of the cup. It is to be noted that the upper guide members are spaced below the lip of the cup to permit the same to be passed or forced outwardly through the aperture 13'. The ridges or guides 35' are broken to form diametrically opposed gaps 37, which are deep enough to permit the cups to be passed by and clear the barriers 17', 18', and the rivets 17'', 18'', where the latter are used.

The actuating means for rotating the spiral springs 40 will now be described:

The device comprises a flat button or knob 20' having a generally solid body portion 21' which is slotted along a diameter to provide a slot 22' adapted to receive the terminal end 42 of spring 40. The knob or cap 20' is provided with a peripheral shoulder or flange 23', which provides a bearing engagement for the bottom coil of the spring 40. On its under or exposed side, the member 20' is formed with a central knob or elevation 24', which, as shown, is of square configuration.

The cap member 20' is set in place and maintained locked in rotatable cooperation with the spring in the following manner: A ferrule 25', comprising a cylindrical body portion 26' with a base or cap section 27', has formed in the latter portion a depressed platform or rim 28' which is

conformed to and adapted to receive the platform or knob 24' of the cap member 20'. The shell or body portion 26' of the ferrule 25' is expanded into an over-sized annulus 29', which is concentric with the body portion 26', and of greater diameter, being of sufficient diameter to receive the everted flange sections 14' of the spring fingers 16' formed at the bottom of the casing 10'. Because of the special configuration of the parts, the ferrule 25' with the button or knob 20' fitted therein is forced over and on the lower end of the casing 10', the spring fingers 16' being forced inwardly during the upward drive or push of the ferrule until the flanged ends 14' of the spring fingers clear the body section 26' and snap into place in the internal groove formed by the annulus or ridge 29', thereby locking the parts together in cooperative interlocking relation. With such a force-fit construction and interlocking, it is practically impossible for the average female user of lipstick to force the parts of the lipstick apart, so that a substantially fool-proof structure is provided.

Due to the special cooperation between the barrier points, pins or bearing surfaces, and their special orientation and cooperation with the turns of spring 40, the latter is not subjected to any untoward binding or other mechanical disadvantages, and a free-moving lipstick carrier is made available.

What is claimed is:

1. A propel-repel lipstick holder comprising a tubular casing, an actuating member on and interlocked with the lower end of the tubular casing, an axially reciprocable lipstick carrier in the casing, a helical compression spring connected to the carrier and the actuating member, and spring guiding and retaining means providing diametral bearing points for the spring vertically displaced by an amount substantially equal to one-half the free pitch of the spring.

2. Spring-retaining means according to claim 1 in which the diametral bearing points for the spring comprise projections on the inner surface of the casing.

3. Bearing projections according to claim 2 comprising integral barrier pins or studs struck up from the casing.

4. Spring-retaining means according to claim 1, in which the diametral bearing points for the spring comprise barrier pins or studs inserted in and secured to the casing.

5. Spring-retaining means according to claim 1, comprising a rectangular frame secured in and to the casing, providing spaced horizontal bearing members, the spacing of the bearing members being substantially equal to one-half the free pitch of the spring threaded therethrough.

6. Casing according to claim 1, in which the base is formed with a plurality of vertical slots.

7. Casing according to claim 6, the slotted base section being formed with an internal horizontal bead defining an external groove.

8. Casing according to claim 7, the slotted and grooved base section forming fingers severally terminating in everted flanges.

9. Actuating member according to claim 1, comprising a rotatable disc, means on the disc for receiving the compression spring in driving relation, and means for locking the said member to said casing and rotatably therein.

10. Actuating member according to claim 9, including a cylindrical collar having a horizontal peripheral groove, and spring-retaining means in the collar.

11. Locking means according to claim 1, comprising a ferrule mounted on and over the bottom of the casing.

12. Ferrule according to claim 11, including a cap portion seating the rotatable disc, and rotatable to actuate the disc.

13. Ferrule according to claim 12, the disc being demountably seated in the cap.

14. A propel-repel lipstick holder comprising an open-ended tubular casing, a plurality of fingers formed at one end of the casing, lipstick carrier in the casing and extendable beyond the other end of the casing, an actuating member fitted within the fingered base of the casing and interlocked therewith, a carrier-actuating helical compression spring secured to the carrier and the actuating member, and means associated with the casing engaging a half coil turn of the spring at diametrically opposed bearing points whereby the coils of the spring between the actuating member and the barrier points are compressed and the coils of the spring are fully expanded between the bearing points and the lipstick carrier.

15. A propel-repel lipstick holder comprising an open-ended tubular casing having an in-turned flange at one end and a plurality of spring fingers at the other end, a horizontal groove in and defined by the said fingers, a lipstick carrier in the casing and extendable beyond the flanged opening, an actuating member fitted within the fingered base of the casing and interlocked therewith, a spring guiding and retaining member fitted in and between opposed slots, said guide incorporating parallel bearing sections spaced a half coil turn from each other, a carrier-actuating coil spring threaded through the guide and secured to and between the carrier and the actuating member, and a sleeve fitted over the base of the tubular casing to serve as a locking member for the fingers and retaining member for the guide.

16. A compression-spring actuated device comprising a casing, an actuated member, a rotatable actuator and a helical compression spring connecting the actuated member and the actuator, and means for holding the bottom coils of the spring under compression and moving the top coils in the casing axially without lateral distortion and binding against the casing wall, said holding means comprising bearing surfaces engaging opposing points of a single coil at substantially one-half the free pitch of the spring.

17. Device according to claim 16 in which the portion of the spring below the lower bearing surface is maintained under compression.

ALBERT GELARDIN.
